UNITED STATES PATENT OFFICE.

JOHN MATTHEW BOWEN, OF TROY, NEW YORK.

SMOKING-PIPE.

1,205,419.

Specification of Letters Patent. Patented Feb. 25, 1919.

Application filed March 27, 1918. Serial No. 225,009.

To all whom it may concern:

Be it known that I, JOHN M. BOWEN, a citizen of the United States, residing at Troy, in the county of Rensselaer and State 5 of New York, have invented certain new and useful Improvements in Smoking-Pipes, of which the following is a specification.

This invention has relation to smoking pipes, and has for an object to provide a 10 pipe designed to prevent the accumulation of moisture in the smoke channel thereby insuring the continuous operation of the pipe without the possibility of it becoming clogged up by accumulations.

15 Another object of the invention is to provide a smoking pipe of the character above described, and constructed in a manner to permit cleaning thereof and to permit thorough ventilation of the pipe while the same 20 is not in use with a view to preventing the pipe from acquiring an obnoxious odor.

A still further object of the invention is to provide a smoking pipe having a pocket formed in the stem for communication with 25 the smoke channel to collect moisture therein, and means whereby the moisture may be readily removed from the pocket and the pipe thoroughly ventilated when not in use.

In addition to the foregoing my invention 30 comprehends improvements in the details of construction and arrangement of the correlative parts to be hereinafter more fully described and particularly set forth in the appended claim.

35 In the accompanying drawings in which similar and corresponding parts are designated by the same characters of reference throughout the several views in which they appear:—

40 Figure 1, is a view in longitudinal section of a smoking pipe constructed in accordance with my invention, and

Fig. 2, is a transverse section thereof taken on the line 2—2 of the preceding figure.

45 With reference to the drawings, 10 indicates the bowl of a pipe and 11 the stem. A smoke channel 12 extends through the stem for communication at one end with the interior of the bowl and for connection at its 50 opposite end with the reduced nipple 13 of the mouthpiece 14. The smoke channel 12 may be formed to extend through the stem along a line descending slightly from the nipple 13 which enters the stem at a point 55 above the central axis of the same. A pocket 15 is formed in the stem at the front end of

the smoke channel and in communication therewith, and running parallel to the bottom of the stem is a second channel 16 terminating at one end within the stem and in 60 communication at its other end with the pocket 15. The upper portion of the pocket communicates with the bowl through a duct 20 which is practically in alignment with the main channel 12. An opening 17 is also 65 formed in the under side of the stem in communication with the channel 16, and mounted in said channel 16 is a plug 18 of rubber or other suitable material adapted to be moved along the channel, in one position to 70 overlap the opening 17, and in another position to uncover said opening. The under side of the plug 18 may be serrated as at 19 to permit the plug to be readily shifted.

It will be obvious, that in use, the moisture in the smoke as the smoke passes through the channel 12 will be condensed on the walls of the channel. It will be noted that the smoke channel is inclined from a point adjacent its point of connection with the mouthpiece 14 downwardly toward the pocket 15. In this manner, the moisture condensed on the walls of the smoke channel will flow into the pocket 15 and accumulate therein. To clean the pipe it is but necessary 85 to shift the plug 18 so as to dispose the same within the rear end of the channel 16 thereby uncovering the opening 17 whereupon the moisture may flow from the pocket and the pocket can be swabbed out by means of 90 any suitable instrument. It will be seen that inasmuch as the pocket 15 is sufficiently large in capacity to permit the accumulation of a considerable amount of moisture, the efficient operation of the pipe will be continued 95 for some time. The accumulation of moisture within the pocket 15 will not interfere with the free passage of smoke through the channel and bowl. When the pipe is not in use the plug 18 may be shifted to uncover 100 the opening 17 whereby the whole interior of the pipe as well as the channel may be thoroughly ventilated thereby preventing the pipe from accumulating an obnoxious odor. In this manner, the pipe will be thoroughly dried also.

While I have illustrated and described my invention with some degree of particularity, I realize that in practice various alterations thereon may be made, and I therefore desire to reserve the right and privilege of changing the form of the details of construc- 110

tion and arrangement of the correlative parts without departing from the spirit of the invention or the scope of the appended claim.

5 Having thus described my invention what I claim as new and desire to secure by Letters Patent is:—

10 A pipe comprising a bowl, stem, and mouth piece, the mouth piece having a nipple at its inner end; the stem having an upper channel open at one end to receive the nipple and inclining downwardly and forwardly, a pocket at the forward end of the channel, and a lower channel leading from the pocket rearwardly and closed at its rear end but

opening through the bottom of the stem; and the bowl having a duct communicating with the upper portion of said pocket; combined with a plug slidably mounted in said second channel across the opening and adapted to be reached through the latter whereby the plug may be moved to the rear to uncover the opening and dump the contents of the pocket. 20

In testimony whereof I affix my signature 25 in presence of two witnesses.

JOHN MATTHEW BOWEN.
